US00D708001S

(12) **United States Design Patent**
Measom et al.

(10) **Patent No.:** **US D708,001 S**
(45) **Date of Patent:** **** Jul. 1, 2014**

(54) **GAS STOVE**

(71) Applicants: **Ty Measom**, Logan, UT (US); **Brett Bennett**, Mantua, UT (US)

(72) Inventors: **Ty Measom**, Logan, UT (US); **Brett Bennett**, Mantua, UT (US)

(73) Assignee: **Logan Outdoor Products, L.L.C.**, Hyde Park, UT (US)

(**) Term: **14 Years**

(21) Appl. No.: **29/455,014**

(22) Filed: **May 16, 2013**

(51) LOC (10) Cl. **07-02**

(52) U.S. Cl. .... **USPC D7/332**

(57) **CLAIM**

The ornamental design for a gas stove, as shown and described.

DESCRIPTION

FIG. 1 is a front isometric view of a gas stove showing our new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The details shown in broken lines form no part of the claimed design.
